UNITED STATES PATENT OFFICE.

JOHN H. STICKELL, OF WILLIAMSON, PENNSYLVANIA.

HORSESHOE.

Application filed September 18, 1926. Serial No. 136,321.

The invention provides a horseshoe having a separable toe calk and integral heel calks of peculiar shape and arrangement to enable the animal to obtain a firm and sure footing upon hard smooth crowned roads and soft gravel surfaces regardless of traveling conditions.

The invention furthermore aims to supply a horseshoe of the character aforesaid which may be produced at a comparatively low cost and which is safe and obviates side slipping as well as front and rear slipping on ice covered or other hard and smooth surfaces.

The invention also provides a horseshoe having calks which are self-sharpening, and so formed as to prevent the wedging of snow, mud, and the like, and which insure a level and even contact with the surface, thereby resulting in easier walking of the animal, even wearing of the calks, and a firm and safe footing at all times and under all road conditions.

While the drawings illustrate a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawings hereto attached, in which,

Fig. 1 is a bottom plan view of a horseshoe provided with calks embodying the invention;

Fig. 2 is a detail sectional view on the line 2—2 of Fig. 1;

Fig. 3 is a view similar to Fig. 1 of a modification, a portion of the horseshoe being broken away; and

Fig. 4 is a detail sectional view on the line 4—4 of Fig. 3 looking in the direction of the arrows.

Corresponding and like parts are referred to in the following description and designated in the several views of the drawings by like reference characters.

The horseshoe may be of any approved or usual construction, and comprises a body 1 having a toe calk 2 and heel calks 3, the latter forming an integral part of the horseshoe, whereas the toe calk 2 is separate from and attached to the horseshoe. The several calks

are of similar formation and are approximately of U-form, the retrorsal ends of the toe calk facing rearwardly and the corresponding ends of the heel calks facing forwardly. The front side of the toe calk is flush with the front side of the horseshoe, whereas the retrorsal ends 4 are inset from the outer and inner marginal edge faces or sides of the horseshoe, and are disposed in parallel relation, whereby to prevent side slipping and present an extended surface for engagement with the road. The inner or rear side of the toe calk is beveled for its full depth, as indicated at 5, thereby preventing snow, mud, and the like from wedging in the space enclosed by the rear hollow side of the calk. While any means may be employed for securing the toe calk to the body of the shoe, it is preferred to provide the calk with integral studs 6 and to provide the toe portion of the shoe with openings to receive the studs, said openings being countersunk to receive the upset or swaged ends of the studs 6 when the calk is in position, as shown most clearly in Figs. 2 and 4 of the drawings.

The heel calks 3 constitute an integral part of the shoe, and are formed by bending the rear terminal portions downwardly, and having the extremities bent forwardly, with the result that the heel calks present a U-form and have the hollow sides facing forwardly. The forwardly bent or retrorsal extremities 8 are parallel with the sides of the respective end portions of the shoe and come flush therewith. The toe calk 2 is of such length and so disposed so that the outer sides of the retrorsal ends 4 are in line with the inner extremities of the heel calks 3, as indicated by the dotted lines a—a and b—b in Fig. 1. This results in an even bearing and uniform distribution of the weight, so that the animal may obtain a level and sure footing with the result that walking is made easy and tilting prevented.

In the modification shown in Figs. 3 and 4 the outline and disposition of the toe calk 2^a and the heel calks 3^a are substantially the same as the corresponding parts shown in Fig. 1, the difference residing in having the rear side of the toe calk 2^a beveled to provide a narrow edge 9, and both sides of the heel calks beveled to provide a narrow edge 10.

It is observed that the retrorsal ends of the several calks cooperate to prevent side

slipping, whereas the intermediate portions prevent slipping forwardly and rearwardly. Obviously there is a cooperation between the component parts of the calks to prevent the animal from slipping in any direction, and the result is the same, whether the surface of the road is smooth, or soft and covered with gravel. By having the toe calk separate from and attachable to the shoe, it may be applied to a worn shoe, or one of any type. A horse shod with shoes having calks embodying the invention is enabled to obtain a firm and sure footing and to walk with ease and an even bearing, regardless of the nature of the road surface and traveling conditions.

Having thus described the invention, I claim:

1. A horseshoe provided with a toe calk extending transversely across the toe portion of the shoe and having its terminal

portions bent rearwardly and inset from the outer and inner marginal edge faces of the shoe, the forward edge face of said calk being flush with the outer edge face of the shoe, and its inner rear side face beveled for its full depth to prevent snow, mud, and the like from wedging in the shoe.

2. A horseshoe having integral heel calks of approximately U-form with the retrorsal ends of the calks parallel with the sides of the shoe, and a separable toe calk of approximately U-form and having its forward side flush with the front of the shoe and the retrorsal ends inset from the outer edge or side of the shoe, the outer sides of the arms of the toe calk being in line with the inner sides of the arms of the respective heel calks.

In testimony whereof I affix my signature.

JOHN H. STICKELL. [L.S.]
